CLARINET ATTACHMENT

Clinton A. Runyon, Jr., Chicago, Ill.

Application October 11, 1943, Serial No. 505,758

7 Claims. (Cl. 84—382)

This invention relates to a clarinet and is more particularly described as a key attachment for an instrument of this kind which makes possible a new fingering of notes to be played by this instrument which is impossible with the arrangement now used, and which makes it possible to finger one note with only one finger which requires the use of two fingers in one instance, and involves the usage of three fingers in other instances. The invention comprises an attachment for one of the keys which is adapted to be engaged by the first finger of the left hand in addition to the key normally engaged by this finger, making it possible to finger this note with only one finger. This is greatly advantageous from the standpoint of technique as it facilitates playing musical passages heretofore considered not only difficult, but practically impossible.

The principal object of the invention is in the provision of a B-flat key attachment engageable with one of the key supporting arms and projecting adjacent one of the holes so that the finger closing it may be extended to engage the projection and depress the arm for operating the B-flat key when desired.

A further object of the invention is to provide an attachment which may be easily applied to existing clarinets and similar instruments without changing the other key operating mechanism.

Another object of the invention is to provide a clarinet with a key attachment of new and improved construction characterized by simplicity of design as well as ease and facility of assembly.

Other objects of the invention and various advantages and characteristics of the present combined instrument and attachment will be apparent from a consideration of the following description.

The invention consists in the several novel features which are hereinafter described and more particularly defined by claims at the conclusion hereof.

In the drawings which accompany and form a part of this specification or disclosure and in which like letters and numerals of reference denote corresponding parts throughout the several views:

Figure 1 and Figure 2 are elevational views one at an angle to the other, illustrating a clarinet with an attachment in accordance with this invention applied to one of the keys thereof in accordance with this invention;

Figure 3 is an enlarged partial view showing the application of the attachment to a key arm;

Figure 4 is a sectional view taken on line 4—4 of Figure 3 illustrating the operation of the keys relating to the attachment;

Figure 5 is a perspective of the attachment 5 apart from the key;

Figure 6 is a sectional view taken on the line 6—6 of Figure 3;

Figure 7 shows several musical passages, difficult to finger without the present invention; 10 and

Figure 8 is a diagrammatic chart which indicates the old fingering, and also the new fingering possible with this attachment.

This invention produces an improved clarinet 15 and particularly improves the fingering and playing technique for certain notes and musical passages. It may be built into a new instrument, and also a specific attachment may be provided, as herein shown and described, which may be applied to clarinets now in use, to give them the same advantages and structure. It is therefore unnecessary to describe the entire construction and operation of a clarinet, which is well known to musicians familiar with this instrument, so 20 that the improved combination and arrangement, and the attachment, will be described as it applies to a Boehm system clarinet.

Referring more particularly to the drawings and to the upper or left hand positions on the 25 instrument, an upper clarinet section 8 is provided with a first finger hole 9, a second finger hole 10, and a third finger hole 11. Between holes 9 and 10 is a B-natural hole 12. Around each of the holes 9 and 10 and 11 are projecting 30 rims 13, 130, and 131 with surrounding grooves 14, 140, and 141 for receiving key rings 15, 16 and 17 respectively. Ring 15 is supported by an arm 18 mounted upon a ferrule section 19 and closes a key 20 attached by an arm 21 to the 35 same ferrule 19 when the ring is seated in its groove.

Around the hole 12 is an angular groove 22 forming an angular rim 23 closed by a pad 24 carried by a key 25 at the end of an arm 26 40 pivoted on a ferrule 27. Key ring 16 is supported by an arm 28 pivoted on a ferrule bar 29, and key ring 17 is supported by an arm 30 secured to ferrule section 31 rotatable on the bar 29. Ferrules 27 and 31 are connected below arm 28 by cross piece 32 which is engaged by arm 28 when key ring 16 is depressed by the second finger.

With this arrangement, B-flat key 25 is closed each time finger rings 16 and 17 are depressed by the left second and third fingers, either separately or together. This operation is entirely 45 50 55

separate and distinct from the operation of key ring 15 and its key 20.

Instead of closing the key 25 on its hole 12 in the manner described, an attachment block 33, as shown more clearly in Fig. 5 is provided with a slot 34 having an angular inner end 35 to fit more closely over the key arm 26 which is also angular in cross section. Extending inwardly to the slot from one outer side is a set screw 36 to engage one angular edge of the arm 26 beyond its widest portion when seated in the slot, thereby holding the block tightly in engagement with the arm. Extending from the side of the block toward the key ring 15 is a bent projection 37 which is positioned near the ring. By extending the first finger of the left hand, it may engage the projection and close the key 25 upon the hole 12 at the same time this finger is depressing the key ring 15 and without removing the finger from the key ring.

In playing the regular Boehm system clarinet, B-flat in the second register involves the use of two or three fingers, such as the indicated passages A and B in Figure 7. Corresponding fingering for these passages is indicated by *a*—*b* on the chart in Figure 8, in which the black spots denote the closed holes and the circles the open holes, those above the line indicating the fingering of the first three fingers of the left hand and those below the line the first three fingers of the right hand.

When the octave or vent key is released, due to the fact that the clarinet is built in twelfths, the same fingering as in *a*—*b* produces low E-flat as indicated at C in Figure 7.

To produce high F-sharp in the third register as indicated in D Figure 7, a variety of fingerings as indicated in M Figure 8, would be tried in the old Boehm system, requiring two, three, or more fingers, with questionable true tones, and as indicated by the chart in Figure 8, a better tone quality is obtained by the left first finger closing its hole 9 and key 20 and also the finger engaging the new attachment of this invention and closing the B-flat key 25.

In thus producing high F-sharp in the third register of the clarinet, an entirely new and heretofore unheard of or impossible fingering is therefore made possible. A better and truer tone pitch on this note is also produced besides facilitating the fingering.

The attachment being easily applied and removed may be easily attached to clarinets now in use and may be incorporated or built in these instruments in the future.

The invention is not to be understood as restricted to the details set forth since these may be modified within the scope of the appended claims without departing from the spirit and scope of the invention.

Having thus described the invention, what I claim as new and desire to secure by Letters Patent is:

1. The combination with a Boehm system clarinet having adjacent finger holes and a hole between them with a key normally open for closing it, the key having an angular supporting arm, and a key arm attachment comprising a block

with a slot to fit over the arm and a projection from the block extending adjacent one of the finger holes so that the key may be closed by the same finger which closes one of the holes.

2. The combination with a Boehm system clarinet and a B-flat attachment therefor comprising a pair of finger holes, a B-flat hole between them and a key supported by an arm in normally open position for closing it, and the removable attachment having a block with a slot to embrace the arm and an extension therefrom to provide a projection from the arm adjacent one of the finger holes for closing the key with one finger without uncovering the hole to which it is applied.

3. The combination with a Boehm system clarinet having a B-flat key adjacent the left first finger hole, and a removable attachment for the key comprising a slotted block for engaging the B-flat key supporting arm having a projection adjacent the finger hole so that the key may be operated by the finger when it also covers the hole.

4. An attachment for the B-flat key arm of a clarinet, which comprises a block with a slot to engage over the arm and means for adjustably connecting it to the arm, and a projection extending from the block to a point near an adjacent finger hole for engagement by the same finger which closes the hole without disengaging the finger therefrom.

5. An attachment for a Boehm system clarinet having a finger hole and an arm supported key for closing a hole adjacent the finger hole, comprising a block with a slot to receive the arm therein, a projection extending from the block, and means comprising a screw insertable at the side of the block for engaging the arm and releasably attaching the block to the arm so that the projection will be adjacent the finger hole for engagement by a finger closing the hole.

6. A B-flat key attachment for a clarinet comprising a block with a slot having an angular inner end to receive an angular key supporting arm therein, a set screw extending from the outer side of the block into the slot to engage an arm therein, and a projection extending from the block and bent to extend in a direction away from the arm to which it is attached and toward an adjacent key.

7. An improved playing system for a clarinet having the ordinary arrangement of ring key closed holes for the first and second fingers of the left hand and a B-flat hole between the two holes closed by an arm supported key and normally operated, in combination with an attachment adjustably secured to the angular arm of the B-flat key and having a block with a slot for engaging over the arm, a screw inserted at the outside of the block for extending into the slot and engaging the angular arm to hold the block thereon, and the block having a projection extending adjacent the key ring of the first finger hole, whereby the first finger may be extended from its position closing the hole to also engage said projection and to close the B-flat key at the same time.

CLINTON A. RUNYON, JR.
